UNITED STATES PATENT OFFICE.

PETER J. PAULY, JR., OF ST. LOUIS, MISSOURI.

DOOR-LOCK.

No. 918,693.

Specification of Letters Patent.

Patented April 20, 1909.

Application filed December 28, 1908. Serial No. 469,638.

To all whom it may concern:

Be it known that I, PETER J. PAULY, Jr., citizen of the United States, residing at St. Louis, State of Missouri, have invented certain new and useful Improvements in Door-Locks, of which the following is a full, clear, and exact description, reference being had to the accompanying drawings, forming a part hereof.

10 My invention has relation to improvements in door-locks; and it consists in the novel details of construction more fully set forth in the specification and pointed out in the claims.

15 In the drawings, Figure 1 is a top plan of a corridor door, showing lever-box in horizontal section; Fig. 2 is a vertical section on broken line 2—2 of Fig. 1; Fig. 3 is an enlarged horizontal section on the line 3—3 of Fig. 2; Fig. 4 is a perspective of the operating handle or lever and parts immediately controlled thereby; Fig. 5 is a vertical section on the line 5—5 of Fig. 4; Fig. 6 is an inner face view of a portion of the gravity or drop-bar; Fig. 7 is an enlarged sectional detail on line 7—7 of Fig. 2; Figs. 8, 9 and 10 are elevational views illustrating three successive stages of operation of the arresting pin for the drop-bar, and of the locking-bolt controlling 30 the corridor-door; Fig. 11 is a horizontal section on the line 11—11 of Fig. 10; and Fig. 12 is a detail section on the line 12—12 of Fig. 10.

The present invention has special application 35 in connection with corridor jail doors, and has for its object to provide means against any possible unlocking of such door, even though the prisoner should accidentally gain access to the lever box or compartment in which the various operating levers for controlling the door, are located.

The invention finds particular application in the case of doors provided with gravity locking-bars which engage the bolts by which 45 the door is locked or secured when closed, such bars requiring a longitudinal shifting to disengage them from the bolts referred to. Since the retraction of the locking-bolts and the shifting of the bar is generally effected by 50 the same lever operating successively in two distinct directions, it is impossible to maintain the bar in such disengaged position for the purpose of retracting the bolts unless some provision be made to temporarily hold 55 the bar in its shifted or disengaged position after the lever has been swung in proper di-

rection to effect the disengagement. In my invention this temporary retention or arrest of the gravity bar can be accomplished only through the release of a spring-bolt or pin by 60 the retraction therefrom of a spring-latch unlocked by a key in possession only of the keeper, so that he alone can shift the gravity-bar to and retain the same in, proper position to permit the retraction of the bolts by 65 which the corridor door is locked. The pin is automatically restored to re-engagement with its latch upon the final closing of the door which is thus dead-locked, all as will hereinafter more fully appear from a detailed 70 description of the invention which is as follows:—

Referring to the drawings, D represents a hinged door opening into the jail corridor C from the passage P in front of the cells A, the 75 free edge of the door being provided with a strike or keeper K which engages the ends of the locking-bolts B protruding through the side wall of the lever compartment or box L in which the operating levers are housed, the 80 box being closed by a door D' as well known in the art. The bolts B here shown are three in number, the top and bottom ones being provided with the ejecting springs 1, 1, coiled about the bolts, and confined between the 85 supporting angle brackets 2, 2, through which the bolts are free to slide, and collars 3, formed on the bolts. At an intermediate point the several bolts are connected with a plate 4 which is braced at the bottom by a 90 triangular plate 5. When the door D is locked the ends of the bolts are concealed by an angle bar 6 secured to the free edge of the door in front of the keeper or strike K. The several features described are well known 95 and form no part of the present invention. The rear ends of the several locking bolts B operate loosely in the adjacent leg of an angle bar 7 in front of the inner face of which reciprocates vertically the locking gravity or 100 drop-bar 8 which is guided in its movements by pins 9 passing through elongated openings o in the bar, other openings o' of a similar character being provided to allow for the free passage therethrough of the several 105 bolts B. When the locking-bar 8 is in its lowest position the portions thereof immediately above the openings o' settle in or engage suitable recesses r formed along the upper walls of the bolts B, said engagement 110 preventing the retraction of the bolts inwardly and hence preventing their with-

drawal from the keeper K, and the door D thus is held in a locked position. Upon a raising of the gravity-bar 8 however, a sufficient distance to disengage the recesses r, the 5 bolts may be pushed inwardly so as to clear the keeper K, and the door may be swung open.

The raising of the drop-bar 8 is effected by the following mechanism:—pivoted to a 10 bracket 10 carried by a plate 11 secured to the side of the lever box L nearest the door D, is a bell-crank lever 12 oscillating in a horizontal plane, one arm of which is coupled to the adjacent end of a horizontal link 13 15 whose opposite end is pivotally secured to one arm of a bell-crank lever 14 oscillating in a vertical plane, and pivoted to the rear wall of the box L. The free end of the opposite arm of the bell-crank 14 is provided with 20 a laterally projecting pin 15 which bears against the under side of a pin 16 projecting from the drop-bar 8. The outer arm of the bell-crank lever 12 is loosely coupled to a link 17 whose forward end is pivotally secured to 25 the disk 20 at the base of a bent operating lever 18 provided with a stud 19 rotatably mounted in the plate 11. It will be seen from the connections described, that by 30 swinging the lever 18 inwardly (plain arrow Fig. 4) through a sufficient angle, the bell-crank 12 will be oscillated in proper direction to push the link 13, which in turn will rock the bell-crank 14 in proper direction to cause the pin 15 to lift the pin 16 and hence 35 raise the bar 8 sufficiently to effect its disengagement from the bolts B. The bolts being disengaged are now free to be retracted or forced inwardly out of engagement with their keeper K. This is accomplished as follows:—At the base of the operating handle 40 or lever 18 is a disk 20 at the top of which is formed a curved slot 21 through which operates a pin 22 projecting from the face of a reciprocating bar 23, the latter being supported 45 by pins 24 secured to the plate 11 and operating through elongated slots 25, 25, in said reciprocating bar. To an inner terminal bracket 26 of said bar is pivotally secured one arm of a horizontally oscillating bell- 50 crank lever 27 pivoted to a bracket 28 which is riveted to the plate 11. The opposite arm of the bell-crank 27 is pivotally coupled to the adjacent bracket 29 of a push-bar 30 whose opposite end is secured to the plate 4 55 connected to the series of bolts B.

The bolts B being as above stated, disengaged from the drop-bar 8, if we now oscillate the handle 18 outwardly as per feathered arrow in Fig. 4, (or in a direction opposite to 60 that for effecting a raising of the drop-bar 8) the end wall of the slot 21 will push against the pin 22 thus forcing the bar 23 inwardly, whereby the bell-crank 27 will be oscillated in proper direction to bear against the push-bar 30, the latter in turn pushing against the

plate 4 to which it is secured, and hence retracting or withdrawing the entire series of bolts B away from in front of their keeper K, and allowing the door D to be swung open and release the prisoners into the corridor. 70 Of course, in order that the bolts B may be retracted, the drop-bar 8 must be kept in its raised position until the recesses r have passed the danger of the bar reengaging the same in the retracting movement of the bolts; 75 for it is obvious that when the handle 18 is reversed to retract the bolts B it at the same time releases the drop-bar 8 (which had been raised with the inward movement of the handle). It therefore follows that some provision must be made after the bar has been raised, to hold the same up temporarily, or long enough to permit the recesses r of the bolts to pass beyond the path of the bar and thereby prevent the bolts from being locked 80 before their retracting movement can begin. This temporary arresting device for the drop-bar, to hold the same out of engagement with the bolts B (to which position it was lifted by the inward stroke of the lever 18) 85 until after their retracting movement has begun is one of the important features of the present invention, and consists of the following mechanism:—Secured to the rear wall of the lever box L at a point below the middle 90 bolt B, is a lock 31 operated by a key 32 which retracts or actuates a spring latch 33, normally forced out by a spring (not shown) this being a form of lock well known in the art and requiring no detailed description. 95 Below the lock casing is secured a bracket 34 between whose terminal ears e, e, is loosely mounted a pin or bolt 35 having an outer terminal rounded head 36 located exteriorly to one of the ears e, the base of which head 100 the latch engages for a retracted position of the pin (Figs. 8, 10). The pin is provided with a collar 37, between which and the adjacent ear e is located a coiled expanding spring 38 which tends to drive the pin toward the gravity-bar 8 and in fact does so 105 when the latch 33 is retracted by the key 32. 110 When the jailer has oscillated the operating lever or handle 18 inwardly to raise the gravity-bar 8, he at the same time with one hand applies the key 32, turning it to disengage the latch 33 from the head 36, whereupon the pin 35 being released is forced toward the gravity-bar 8, the latter being provided at the proper point with an opening h 115 to receive the end of the pin 35 which thus arrests the bar 8 against a return movement after being once raised to release the bolts B (Fig. 9). The bar 8 thus temporarily arrested, permits the operator to now swing the lever 18 in the opposite or outward direction to effect retraction of the bolts as 120 already explained, for purposes of freeing the keeper K of the door D, and allowing the latter to open. With the retracting or in- 125 130

ward movement of the bolts B however, the pin 35 is automatically restored to its original position in front of the spring latch 33 as follows:—When the arresting pin 35 is first released by a retracting movement of the latch 33, the subsequent release of the latch by the operator causes the bevel end of the latch to spring in front of the head 36 (Fig. 9). Now, the middle bolt B is provided on the side with a pair of pins p , p , between which is disposed the upper arm of a releasing lever 39 pivoted to the box wall, the lower arm terminating in a forked end which spans the pin 35 behind the collar 37. After the bolts have been retracted or forced inward sufficiently to bring the recesses r thereof out of the path of the gravity bar 8, (Fig. 10), the outer pin p strikes the lever 39 oscillating it in proper direction to cause its forked end to press against the collar 37 and force the pin 35 back to its original position, the rounded surface of the head 36 forcing the latch 33 inwardly until the latter slips off the edge of such rounded surface and again automatically drops back behind the flat base of the head (Fig. 10). Of course, upon release of the lever 18 after the full retraction of the bolts and the opening of the door D, the bolts spring back to their outward position under the action of their ejecting springs 1, 1, allowing the gravity-bar 8 (released from the arresting pin as described) to again drop back into engagement with its recesses r of the bolts, the parts being restored to original position (Fig. 8). Obviously the door D (if opened) can not be slammed shut, since the bolts are again locked against movement, but to lock the door, the operator simply imparts with one hand an inward oscillation or stroke to the lever 18 which raises the bar 8 to disengaging position, and with the other hand applies the key 32 to the latch 33 retracting the latter from behind the head 36 of the pin 35, allowing the latter to snap into engagement with the gravity-bar. The bolts being now free from their locking bar 8, the door may be slammed against the outer protruding ends of the bolts, the keeper K driving them inwardly (a movement corresponding to the retracting movement of the bolts for purposes of opening the door) in which inward movement the pin 35 is released (as in Fig. 10), thus freeing the gravity bar 8, which, after the bolts have sprung outwardly in front of the keeper on the complete closing of the door, drops back into its recesses r on the bolts, and the door is dead-locked (Fig. 8). And should the lever-box door D' be left open accidentally, the prisoner could not open the corridor door D even though he could get access to the lever 18, because the bar 8 will not stay up to allow the bolts B to be retracted unless temporarily held up by the pin 35, which can only be released by

the key 32 in the pocket of the jailer. Should the prisoner succeed in oscillating the lever 18 sufficiently to raise the bar 8, the moment he swung the lever in the opposite direction to retract or push in the bolts, the bar would instantly fall back into its notches or recesses r on the bolts, and the latter could not be moved. It therefore requires a key, or some equivalent means to release the arresting pin by which the gravity bar may be temporarily held up until the bolts are retracted to permit the corridor door to open. Of course, the principle can be applied to any door, and is not restricted to corridor doors.

Having described my invention, what I claim is:

1. In combination with a sliding locking-bolt, a gravity or drop bar normally engaging the bolt against movement, means for disengaging the bar from the bolt, and devices for temporarily arresting the bar against a return to its original position pending a movement of the bolt in one direction.

2. In combination with a sliding locking-bolt, a gravity or drop bar normally engaging the bolt against movement, means for disengaging the bar from the bolt, and devices independent of the disengaging means for temporarily arresting the bar against a return to its original position pending a movement of the bolt in one direction.

3. In combination with a door, a sliding bolt locking the same, a gravity or drop bar normally engaging the bolt against retraction from the door, means for disengaging the bar from the bolt, and subsequently retracting the bolt from the door, and devices for temporarily arresting the return of the bar to its engaging position with the bolt, during the retracting movement of the latter.

4. In combination with a sliding locking-bolt, a gravity or drop-bar normally engaging the bolt against movement, means for disengaging the bar from the bolt, devices for temporarily arresting the bar against a return to its original position pending a partial movement of the bolt in a given direction, and subsequently disengaging the arresting device with a continuation of the movement of the bolt in the same direction.

5. In combination with a door, a sliding bolt locking the same, a gravity or drop-bar normally engaging the bolt against retraction from the door, means for disengaging the bar from the bolt, and subsequently retracting the bolt from the door, devices for temporarily arresting the return of the drop-bar to its engaging position with the bolt during a part of the retracting movement of the latter, and subsequently disengaging the arresting device with a continuation of the retracting movement of the bolt.

6. In combination with a sliding bolt, a gravity or drop-bar normally engaging the

bolt against movement, means for raising the bar for releasing the bolt, and a spring-actuated latch - controlled pin operating across the path of the drop-bar for arresting 5 the bar against dropping when raised sufficiently to release the bolt.

7. In combination with a sliding bolt, a gravity or drop-bar normally engaging the bolt against movement, means for raising 10 the bar for releasing the bolt, a spring-actuated pin for arresting the bar against dropping when in its raised position, and a key-operated spring-latch for releasing the pin.

8. In combination with a sliding bolt, a 15 gravity or drop-bar normally engaging the bolt against movement, means for raising the bar to effect release of the bolt, a spring-actuated latch-controlled pin for arresting the bar against dropping when in its raised 20 position, a spring-latch retractable to release the pin, and intermediate connections between the bolt and pin for restoring the latter into locked engagement with the latch upon a sufficient movement of the bolt to 25 shift the portion normally engaged by the bar out of the path of said bar.

9. In combination with a sliding bolt, a gravity or drop-bar normally engaging the bolt against movement, means for raising 30 the bar to effect release of the bolt, a spring-actuated latch-controlled pin for arresting the bar against dropping when in its raised position, a yielding latch retractable to release the pin, a releasing lever pivoted at an 35 intermediate point and having one arm engaging the pin, and the opposite arm in position to be oscillated by the movement of the bolt, the latter being adapted to trip or oscillate the lever with a movement sufficient 40 to shift the portions thereof normally engaged by the bar out of the path of said bar.

10. In combination with a sliding bolt, a gravity or drop-bar normally engaging the 45 bolt against movement, an oscillating lever, intermediate connections between said bar

and lever for raising the bar to effect release of the bolt upon a movement of the lever in one direction, means interposed between the lever and bolt for retracting the bolt upon a 50 movement of the lever in the opposite direction, independent means for arresting the bar against dropping during the retracting movement of the bolt, and intermediate devices between the bolt and arresting means 55 for forcing the latter out of engagement with the bar upon a sufficient advance of the bolt to bring the devices carried thereby and normally interlocking with the bar out of the path of the bar.

11. In combination with a sliding bolt, a gravity or drop-bar normally locking the bolt against movement, means for raising the bar to effect release of the bolt, means for retracting the bolt, a lock provided with 60 a key-operated spring-latch, a spring-controlled pin having a rounded head, the bottom of the head normally engaging the latch and holding the pin against movement, but free to release the pin upon retraction of the 65 latch by the key, the bar being provided with an opening or socket to receive the released pin while the bar is in its raised position, a lever pivoted at an intermediate point and having one arm in engagement 70 with the pin, a pair of projections on the bolt between which the opposite arm of the lever is confined, one of said projections being adapted to impinge on the lever-arm and oscillate the latter in a direction to force the 75 pin out of engagement with the bar, at a given point in the retracting movement of the bolt, the rounded head of the pin passing by the yielding latch and causing the latter to resume its original position behind said 80 head, substantially as set forth.

In testimony whereof I affix my signature, in presence of two witnesses.
